UNITED STATES PATENT OFFICE.

MAXIMILIAN G. F. SÖHNLEIN, OF SANTIAGO, CHILE, ASSIGNOR TO ALLIS-CHALMERS MANUFACTURING COMPANY, OF MILWAUKEE, WISCONSIN, A CORPORATION OF DELAWARE.

APPARATUS FOR CONTROLLING THE FLOW OF ORE THROUGH ROASTING FURNACES.

Application filed May 17, 1920. Serial No. 382,680.

To all whom it may concern:

Be it known that I, MAXIMILIAN G. F. SÖHNLEIN, citizen of the Netherlands, residing at Santiago, in the Republic of Chile, have invented certain new and useful Improvements in Apparatus for Controlling the Flow of Ore Through Roasting Furnaces, of which the following is a specification.

This invention relates to the treatment of ores by the roasting process wherein the sulphides of metals are converted into oxides by exposing them to the action of oxygen from the air and stirring by mechanical means so as to expose continually fresh grains of ore to the air. This process, as ordinarily carried out, is continuous, ore being fed at one side or the top of the furnace and being moved through the furnace by displacement. Where special conditions are required, as for instance, an incomplete state of oxidation, or oxidation of one mineral with preference to another, or chloridizing is done after roasting, it is difficult to maintain the exact conditions in the furnace for doing the proper work, and a slight variation of conditions will cause the furnace to deliver an unsuitable product. If this happens there is no remedy that will work instantly, because it takes considerable time for the furnace to be readjusted, and in the meantime it continues discharging an unsuitable product.

My present invention is directed to overcoming the above recited defects by dividing a roasting furnace into sections independent of each other and separated by sliding doors. The process can be carried out in two types of furnaces, the first one being the reverberatory type, and the second the superimposed hearth type. The accompanying drawings illustrate the two kinds of apparatus suitable for carrying out my invention, and referring thereto:

Fig. 1 is a vertical longitudinal diagrammatic section of a reverberatory roasting furnace to which the invention has been applied.

Fig. 2 is a horizontal diagrammatic section of the reverberatory furnace shown in Fig. 1.

Fig. 3 is a vertical diagrammatic section of a superimposed hearth roasting furnace to which the invention has been applied.

Fig. 4 is a horizontal diagrammatic section of a superimposed hearth furnace shown in Fig. 3.

Referring to Figures 1 and 2; 1, 2, 3, 4, 5 and 6 are the rabble arms which stir the ore in the furnace; 7 is the arch and 8 the hearth. The latter is built in several steps, going down in the same direction in which the ore is moved through the furnace. Each pair of rabble arms serve one section which is separated from the next one by the vertical sliding doors 9 and 10. When these doors are closed gases may escape freely through the spaces above them but the ore is confined to the section in which it finds itself, and it can only pass to the section lower down if the door is opened by a lever from the outside.

Referring to Figures 3 and 4, 11 is the arch, and 12 are the three superimposed hearths; 13, 14, 15, 16, 17 and 18 are the rabble arms which are attached to the two spindles 19 and 20, and the sliding doors, which in this case are placed horizontally, are Nos. 21, 22, 23, 24, 25 and 26.

The process may be carried out in the described apparatus as follows: after heating the furnace by burning fuel on the hearths, a charge of ore is introduced on the first hearth, and worked down to the second hearth by opening the sliding door. When it has arrived on the second hearth the door is closed again, and another charge of ore fed on the first hearth. The charge on the second hearth is then passed on to the third hearth by opening the door between those two hearths, and after closing it again, the charge from the first hearth is passed to the second by opening the door between the first two hearths. After closing that door, a new charge of ore is fed on the first hearth, and the furnace is operated with a charge on each hearth, until the charge on the last hearth has reached the state of oxidation that is desired, and is withdrawn from the furnace, or first submitted to an auxiliary process such as chloridizing, and then withdrawn.

After this, the charges are again moved forward in the furnace and fresh ore is fed on the first hearth.

I declare that heretofore there has been no roasting furnace arranged so as to secure the positive control of the state of oxidation

of the charge by the means indicated in these claims, therefore, what I claim is the following:

1. In a roasting furnace, a plurality of hearths each having a discharge conduit communicating with a succeeding hearth, a door in the discharge conduit of each hearth for positively confining material in said hearths, means for agitating material confined in said hearths, and means for effecting operation of said doors from the exterior of said furnace.
2. In a roasting furnace, a plurality of hearths each having a discharge conduit communicating with a succeeding hearth, a door in the discharge conduit of each hearth for positively confining material in said hearths, common means for agitating material confined in each of said hearths and for transporting said material through each of said hearths, and means for effecting operation of said doors from the exterior of said furnace.
3. In a roasting furnace, a plurality of hearths each having a discharge conduit communicating with a succeeding hearth, a door in the discharge conduit of each hearth for positively confining solids and liquid in said hearths while permitting escape of gas, means for agitating material confined in said hearths, and means for effecting operation of said doors from the exterior of said furnace.
4. In a roasting furnace, a plurality of

hearts each having a discharge conduit 35 communicating with a succeeding hearth, a door in the discharge conduit of each hearth for positively confining material in said hearths, means for simultaneously agitating material confined in all of said hearths, and 40 means for effecting operation of said doors from the exterior of said furnace.

5. In a roasting furnace, a plurality of hearths each having a discharge conduit communicating with a succeeding hearth, a door in the discharge conduit of each hearth for positively confining material in said hearths, means for agitating material confined in said hearths, and means for effecting independent manipulation of said doors 50 from the exterior of said furnace.

6. In a roasting furnace, a plurality of hearths each having a discharge conduit communicating with a succeeding hearth, a door in the discharge conduit of each hearth 55 for positively confining solids and liquids in said hearth while permitting escape of gas, common means for simultaneously agitating and transporting the material confined in all of said hearths, and means for 60 effecting independent manipulation of said doors from the exterior of said furnace.

In testimony whereof I affix my signature.

M. G. F. SÖHNLEIN.
